CHARLES FAWCETT BENNION, OF LEICESTER, ENGLAND, ASSIGNOR TO UNITED SHOE MACHINERY COMPANY, OF PATERSON, NEW JERSEY, A CORPORATION OF NEW JERSEY.

SHOE-BEATING MACHINE.

1,197,594.

Specification of Letters Patent. Patented Sept. 12, 1916.

Application filed February 25, 1913. Serial No. 750,545.

To all whom it may concern:

Be it known that I, CHARLES F. BENNION, a subject of the King of England, residing at Leicester, Leicestershire, England, have 5 invented certain Improvements in Shoe-Beating Machines, of which the following description, in connection with the accompanying drawings, is a specification, like reference characters on the drawings indicating like parts in the several figures.

This invention relates to machines for beating or pounding up boots and shoes and is intended to increase the efficiency of such machines by provision for automatic adjustment to the varying condition of the different parts of work being beaten of a tool which may rest substantially continuously upon the surface being treated while it receives beating impulses, thus insuring a more 20 thorough operation on all parts of the work and at the same time rendering it easier to manipulate the work presented to the machine.

An example of the type of machine for 25 which this invention has been adapted is shown in United States Letters Patent No. 1,009,721, granted November 28, 1911. That machine is equipped with a beating device having a working face which maintains a 30 constant relation to the direction of movement of the device.

A feature of the present invention consists in a beating tool having a work engaging member that is pivotally supported near 35 one edge and is yieldingly supported near its other edge to enable it to move for adapting its angular position to the surface with which it contacts, combined with means for imparting to the tool rapid percussional 40 pulses against the work while remaining in substantially continuous contact with the work.

Another feature of this invention consists 45 in a tool which has two coöperating acting faces which are approximately at right angles to each other, one face being adapted to engage the shoe bottom and the other face being adapted to engage the side of the shoe. The tool is rapidly reciprocated so that a 50 shoe when pressed against it will receive a series of blows from the said faces and thereby be pounded up and have its edge and the adjacent portions of the side and bottom properly shaped.

55 In the tool as constructed in accordance

with a feature of this invention the acting faces are located on parts pivoted together in such a manner that the angle which the faces subtend will be varied to suit the angular relationship of the different parts of the work as they are operated upon by the tool. When the tool with its acting faces thus arranged is used on the heel seat of the shoe, where the angle between the bottom and the sides of the work on either side of the edge varies, the relationship of the acting faces of the tool will automatically be changed to suit the different portions of the heel seat as they are brought into contact therewith and consequently the faces of the tool will simultaneously fully contact with the material at both sides of the edge, or with the adjacent surfaces of the bottom and side faces of the lasted shoe. Preferably the tool is constructed with that part which is provided with one face immovable as regards its angular position, the part having the other face being pivoted to the immovable part and pressed forwardly by a spring 70 plunger or like device. According to the 75 illustrated construction embodying this feature of the invention the angularly movable part is pivoted to the stationary part about an axis that is parallel to both acting faces and that is at or approximately at the junction of the said acting faces so that the maximum beating effect may be localized 80 close to the angle.

A convenient construction of a machine 85 embodying the invention in which the face that engages the shoe bottom is fixed and the face that engages the side of the shoe is pivoted will now be described with the aid of the accompanying sheet of drawings. It 90 must be understood, however, that this description is merely illustrative of the preferred way of carrying the invention into effect and that the invention is not confined to the precise construction or to the exact arrangement of the parts.

In the drawings:—Figure 1 is a transverse section through a last carrying a shoe with the tool shown in operative relationship thereto at one side, and Fig. 2 is an end view of the tool regarded in the direction of its 95 acting faces.

In this embodiment of the invention there is a rod 2 which is mounted to slide freely in bearings in the machine frame. The end 3 of the rod 2 is arranged to come within 100 105 110

range of the path of motion of a ring of rolls 4 mounted in a carrier not shown in the drawings but secured on a rapidly rotating shaft. The outer end of the rod 2 is 5 provided with a head or extension 5 in which is bored a transverse recess 6 of circular form in cross section, the center line of the said recess preferably intersecting the center line of the rod and the recess being 10 sunk within the head 5 to rather more than half its diameter. Within the bore of the recess 6 is received the cylindrical shaped end 7 of the movable part 8 of the tool. The portion of the head 5 from the line of opening 15 of the recess forms an acting face 10 of the tool which as shown in the drawings extends outwardly at an oblique angle to the line of reciprocation of the tool. The movable part 8 is normally maintained at substantially the same angle as the face 10 to the line of reciprocation of the tool and at approximately a right angle to the portion 10 by a plunger 12. The plunger preferably is located in a recess 14 in a downwardly 20 extended portion 15 of the head, a spring 16 being located in the recess 14 at the back of the plunger to propel it forward. The movable part of the tool 8 is prevented from being pushed by the spring plunger 12 beyond 25 its normal angular position by pins 18 which are passed through openings in extensions of the cylindrical shaped ends 7 of the movable part, the said extensions projecting beyond the sides of the head 5 so that the pins 30 18, passed therethrough are held in contact with other stop pins 19 projecting from the sides of the head 5. The acting face of the movable part of the tool may be concaved or recessed as at 20 to adapt itself to the curvature 35 of the side face of a shoe.

In operation, when the work is pressed against the tool, the latter will be moved inwardly to bring the end of the rod 2 under the influence of the rotating rolls whereby a 40 series of blows will be imparted to the work. Should the angular relationship of the side and bottom of the part of the work being operated upon vary the movable part 8 of the tool will be moved more or less in opposition to the spring plunger 12 to enable the 45 relationship of the acting faces 10, 20 of the fixed and movable parts respectively to be altered to adapt themselves to the angular condition of the part of the work being dealt with.

Having thus explained the nature of my said invention, I claim as new and desire to secure by Letters Patent of the United States:

60. 1. A shoe beating machine having, in combination, a beating tool that comprises two parts having angularly disposed acting faces, one of such parts being pivoted to the other part about an axis that is substantially parallel to both acting faces and that is at

or approximately at the junction of the said acting faces, mountings adapted for holding the tool continuously against the edge of a shoe bottom, and operating means imparting a rapid succession of percussional impulses to the tool while it is so held against the work. 70

2. In a machine of the class described, a shoe beating tool comprising an endwise reciprocating member having a beating face 75 extending at an angle to the direction of reciprocation of the member, a part pivoted to said member and having a co-operating beating face normally forming substantially the same angle with the direction of reciprocation of said member, means for operating said tool to cause said faces to beat the stock on opposite sides of the bottom edge line of a shoe, and means adapted to yield to permit movement of the pivoted 80 part of the tool for increasing the angle between said two beating faces to enable the tool to beat the material adjacent to the edge of the shoe bottom at different parts of the shoe irrespective of the angle formed by 85 the bottom and side faces of the shoe. 90

3. In a machine of the class described, the combination with a shoe beating tool adapted to have substantially continuous contact with the work and to act progressively along the surface being treated, said tool having a work engaging member that is pivotally supported near one edge and is yieldingly supported near its other edge to enable it to move for adapting its angular 95 position to the surface with which it contacts, of means for imparting to said tool rapid percussional impulses against the work while the tool remains in substantially continuous contact with the work. 100

4. A machine of the class described having, in combination, a tool self adaptable in shape to the angular edge of a lasted shoe at different portions of the shoe bottom, mountings for the tool adapted to hold it in 110 substantially continuous contact with the work, and means for imparting to the tool rapid percussional impulses toward the work while in substantially continuous engagement with the work. 115

5. A machine of the class described having, in combination, a tool comprising two plates presenting acting surfaces normally disposed approximately at right angles to each other and relatively movable about a 120 center located near the junction of said acting faces to vary the size of the angle, and means to impart rapid vibrations to said tool while maintaining it in continuous contact with the work between vibrations. 125

6. A machine of the class described having, in combination, a movable support having a beating face rigidly connected therewith and extending at an oblique angle to the direction of the movement of the support 130

- a beating member having an acting face extending from said first mentioned face at a similar angle to said direction of movement and connected to said support to turn about 5 a center substantially at the junction of said acting faces, means tending to hold said movably mounted beating member yieldingly toward the rigid beating face, and mean for actuating the support to cause the 10 angular edge of a shoe to be beaten by said faces substantially as described.
7. A machine of the class described having, in combination, a tool comprising acting faces located on parts pivoted together 15 in such a manner that the angle which the faces subtend will be varied to suit the angular relationship of the different parts of the work as they are operated upon by the tool, and means for actuating the tool arranged to apply force to the tool in a direction making substantially equal angles with each of said acting faces.
8. A machine of the class described having, in combination, a beating tool for the 20 purpose stated comprising an angularly immovable part having an acting face, and a part having a coöperating acting face and which is pivoted to the said immovable part
- about an axis that is parallel to both acting faces and that is at or approximately at the junction of the said acting faces so that the maximum beating effect may be localized close to the angle. 30
9. A machine of the class described comprising, in combination, a reciprocatory tool having work engaging portions arranged relatively to the direction of movement of the tool to beat with substantially equal effect the stock on opposite sides of the bottom edge line of a shoe, said work engaging portions being relatively movable to vary the angle between their beating faces, yielding means arranged to insure normally a relatively small angle between said beating faces and to permit said angle to be increased through engagement of the tool with the work, and means for imparting beating movements to the tool. 35
- 40
- 45
- In testimony whereof I have signed my name to this specification in the presence of two subscribing witnesses.
